DESIGN FOR A TABLE

William J. Conwell, Elwood, Ind., assignor to G. I.
Sellers and Sons Company, Elwood, Ind.

Application May 22, 1936, Serial No. 62,782

Term of patent 3½ years

To all whom it may concern:

Be it known that I, William J. Conwell, a citizen of the United States, residing at Elwood, in the county of Madison and State of Indiana, have invented a new, original, and ornamental Design for a Table, of which the following is a specification, reference being had to the accompanying drawing, forming part thereof in which:—

The distinctive features of the design consist in a top having an edge projecting beyond the apron which is made with rounded corners with the legs set inwardly of the ends of the table on the apron, the said legs having bevelled top portions and outwardly disposed longitudinally arranged ribs.

I claim:

The ornamental design for a table as shown and described.

WILLIAM J. CONWELL.
